(57) **CLAIM**

We claim the ornamental design for a ceiling recessed type ventilating fan, as shown and described.

DESCRIPTION

FIG. 1 is a front perspective view of a ceiling recessed type ventilating fan of the present invention;

FIG. 2 is a front view thereof;

FIG. 3 is a top view thereof;

FIG. 4 is a bottom view thereof;

FIG. 5 is a first side view thereof; and,

FIG. 6 is a second side view thereof.

The broken line showing of rear portions of a ceiling recessed type ventilating fan and a light is included for the purpose of illustrating environmental structure and forms no part of the claimed design.
